EMERGENCY TRIPPING DEVICE

Donald F. Warner, Lynn, Mass., assignor to General Electric Company, a corporation of New York

Application October 2, 1935, Serial No. 43,227

6 Claims. (Cl. 74—3)

The present invention relates to emergency tripping devices or emergency speed governors, such as are used, for instance, in connection with elastic fluid turbines to effect shutting or controlling of an inlet valve for elastic fluid as the speed of the turbine rises beyond a predetermined fixed value.

The object of my invention is to provide an improved construction and arrangement of emergency tripping devices which is simple in design, reliable in operation, and can be manufactured at comparatively low cost.

For a consideration of what I believe to be novel and my invention, attention is directed to the following description and the claims appended thereto in connection with the accompanying drawing.

In the drawing, Fig. 1 is a somewhat diagrammatic view, partly in section, of an emergency speed tripping device or governor, in accordance with my invention, and Fig. 2 shows certain elements of the device in a different position.

The device includes a casing having a lower half 10 and an upper half 11 with a cover 12, suitably fastened to the upper half 11. A governor shaft 13 projects into the casing. The shaft may be secured to or form a part of a shaft of a turbine or like prime mover to be controlled. A flyweight in the form of a plunger 14 with a disc 15 at its lower end is disposed in a radial bore or recess 16 in the shaft 13 and held therein by means of a screw plug 17.

The flyweight 14 is biased inwardly; that is, towards the center of the shaft, by means of compression spring 18 surrounding the plunger 14 and bearing against the disc 15 and the plug 17. The arrangement so far described is typical of any emergency speed tripping device.

During normal operation, the flyweight or plunger 14 is biased inwardly against the centrifugal force acting thereon. As the speed of the shaft 13 rises beyond a predetermined value, said centrifugal force overcomes the biasing force of the compression spring 18 and thereby permits radial outward movement of the plunger 14. The end of the plunger 14, as clearly indicated, projects through an opening 19 in the plug 17. The shaft 13 and the plunger 14 represent in substance a speed responsive mechanism.

Means are provided in co-operative relation with the plunger 14 and moved thereby as the plunger is forced outward to effect tripping of certain elements which in turn cause adjusting of an element to be controlled. The means operating with the plunger 14 comprise, in ac-

cordance with my invention, a combined trigger and tripping post 20 which in the present instance has the form of a bar. Thus, a trigger and tripping element are united to form a single element 20. In analyzing this element, it is noted that the lower part thereof acts as a trigger element and the upper part thereof acts as a tripping post or element. From another viewpoint, the trigger of my emergency tripping device is formed as an integral projection of the 10 tripping post. The combined trigger and tripping post projects through an opening 21 in the cover 12 and a cylinder 22 integrally united with the cover 12. The lower portion of the combined trigger and tripping post, the trigger, is arranged 15 in co-operative relation with the flyweight 14. The upper end of the combined trigger and tripping post is connected by a pivot 23 to an arm of a bell crank lever, which latter is held on a fulcrum 24 secured to the cover 12. The other 20 arm of the bell crank lever is pivotally connected to a link 25 which may be connected to an element to be controlled, such as in the example mentioned above, to an inlet valve of an elastic 25 fluid turbine. The combined trigger and tripping post or bar forms a shoulder 26, which in operative position as shown in Fig. 1, rests on a stop, or like element, which in the present instance is formed by a plate 27 secured to the lower end of the cylinder 22 by means of bolts 30 28. If the combined trigger and tripping post is moved towards the right; that is, out of engagement with the plate 27, it is forced downward by the action of a compression spring 29 surrounding the combined trigger and tripping 35 post and disposed within the cylinder 22. The upper end of the spring bears against the plate 12 and the lower end bears against a cross-pin 30 secured to the combined trigger and tripping post and having ends disposed in slots 31 and 40 32 respectively of the cylinder 22. As will be clearly noted in the drawing, the right-hand end of the pin 30 is heavier than the left-hand end. This is an important feature of my invention in that it causes the compression spring 29 45 to become compressed more on its right-hand side than on its left-hand side. This difference in compression between the two sides of the spring 29 effects a twist, or turning action, of the combined trigger and tripping post in clockwise 50 direction so that the lower end of said combined trigger and tripping post is forced towards the left and thereby assures engagement between the shoulder 26 and the plate or stop 27. From another viewpoint, the compression spring 29 55

serves two purposes, first, to effect downward movement of the tripping post during emergency conditions, and second, to maintain the trigger and tripping post in operative position. Hence, 5 the compression spring 29 represents in substance a combined trigger and tripping post spring and the crosspin 30 broadly constitutes a means for maintaining compression of the spring 29 and for compressing one side of the 10 spring more than the other.

During operation, that is during rotation of the shaft 13, the device remains in the operative position shown in Fig. 1 until the speed of the shaft 13 rises beyond a predetermined value. 15 If this occurs, the flyweight 14 moves radially outward into engagement with the lower end of the combined trigger and tripping post and thereby forces this lower end towards the right. This causes disengagement between the shoulder 20 26 and the stop or plate 27, permitting the compression spring 29 to force the combined trigger and tripping post downward, resulting in counterclockwise turning movement of the bell crank lever and movements towards the left of 25 the link 25. In case this link is connected to an elastic fluid turbine inlet valve, the arrangement is such that said valve is shut. Downward movement of the combined trigger and tripping post and disengagement between the shoulders 30 26 and the stop or plate 27 is facilitated by the provision of an inclined surface 33 adjacent the shoulder 26. From another viewpoint, the inclined surface 33 indicates a portion cut away from the lower part of the tripping post so that 35 slight movement of the flyweight effects tripping of the device. Fig. 2 shows the arrangement when tripped. Resetting is accomplished manually by forcing the combined trigger and tripping post upward against the force of the spring 29 until the shoulder 26 engages the plate 27. The compression spring 29, together with the flyweight 14, represents means for effecting an 40 automatic tripping in response to certain speed or like emergency conditions.

45 Tripping may also be effected manually. To this end, a cam 34 is provided within the lower casing half 16 in co-operative relation with the lower end of the combined trigger and tripping post. The cam 34 may be turned by means of a handle 35 disposed outside the casing. Turning of the cam forces the lower end of the combined trigger and tripping post towards the right, whereby the shoulder 26 is moved from its engagement with the plate 27, thus permitting 50 downward movement of the combined trigger and tripping post by the action of the compression spring 29 as heretofore described.

Having described the method of operation of my invention, together with the apparatus which 55 I now consider to represent the best embodiment thereof, I desire to have it understood that the apparatus shown is only illustrative and that the invention may be carried out by other means.

What I claim as new and desire to secure by 60 Letters Patent of the United States, is:

65 1. An emergency tripping device including the combination of a speed responsive element, a combined trigger and tripping post in co-operative relation with said element, and a combined trigger and tripping post spring for maintaining the trigger and tripping post in co-operative 70 relation with said element and for effecting

movement of the combined trigger and tripping post in response to movement of said element.

2. An emergency tripping device including the combination of a casing, a rotatable shaft projecting into the casing, a flyweight on the rotatable shaft, a combined trigger and tripping post in co-operative relation with the flyweight and having a shoulder, a stop normally engaging the shoulder, and a combined trigger and tripping post spring for maintaining the combined trigger and tripping post in co-operative relation and for moving the combined trigger and tripping post in response to movement of the flyweight. 5

3. An emergency tripping device including the combination of a bar, an element to be controlled connected to the bar, a stop for normally holding the bar in a certain position, a mechanism for disengaging the bar from the stop in response to an emergency condition, and a single spring 20 for normally maintaining engagement between the bar and the stop and for effecting tripping of the bar after the bar has been disengaged from the stop. 15

4. An emergency tripping device including the combination of a bar, an element to be actuated by the device connected to the bar, a stop for normally holding the bar in a fixed position, means for effecting disengagement between the bar and the stop in response to an emergency condition, a spring for tripping the bar after 30 disengagement between the bar and the stop, and means including the aforementioned spring for normally maintaining engagement between the bar and the stop. 35

5. An emergency tripping device including the combination of a shaft having a radial opening, a plunger held in and projecting through the opening, means including a spring surrounding the plunger to bias it radially inward against 40 the action of centrifugal force, a combined trigger and tripping post in the form of a bar having a portion in co-operative relation with the plunger, a casing for the combined trigger and tripping post, a stop secured to the casing engaging the combined trigger and tripping post to normally hold it in a fixed position, the combined trigger and tripping post being disengaged from the stop in response to a certain movement of said plunger, and means for effecting 45 tripping of the disengaged combined trigger and tripping post, said last-named means comprising a cross-pin secured to the combined trigger and tripping post and a compression spring between the cross-pin and the casing. 50

6. An emergency tripping device including the combination of a casing forming a stop, a bar forming a combined trigger and tripping post, a stop on the casing engaging the bar to normally hold the bar in a certain position, means including a shaft and a flyweight held on the shaft for disengaging the bar from the stop in response to an emergency condition, and means for normally maintaining engagement between the stop and the bar and for effecting tripping of the 65 bar after the bar has been disengaged from the stop, said last-named means consisting of a spring surrounding the bar and means for effecting different compressions of the two sides 70 of the spring. 60
